WHEEL

John W. Mason, Detroit, Mich., assignor to Motor Wheel Corporation, Lansing, Mich., a corporation of Michigan

Application December 11, 1953, Serial No. 28,020

Term of patent 7 years

(Cl. D14—30)

To all whom it may concern:

Be it known that I, John W. Mason, a citizen of the United States, residing at Detroit, in the county of Wayne and State of Michigan, have invented a new, original, and ornamental Design for Wheel, of which the following is a specification, reference being made to the accompanying drawings, forming part thereof.

Fig. 1 is a side elevational view of a wheel, showing my new design.

Fig. 2 is an enlarged sectional view taken on line 2—2 of Fig. 1.

Fig. 3 is an enlarged sectional view taken on line 3—3 of Fig. 1.

Fig. 4 is a perspective view of the wheel shown in Fig. 1.

I claim:
The ornamental design for a wheel, as shown.
